UNITED STATES PATENT OFFICE.

RUDOLF E. HELLMUND, OF SWISSVALE, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,347,905.

Specification of Letters Patent. Patented July 27, 1920.

Application filed March 9, 1917. Serial No. 153,549.

To all whom it may concern:

Be it known that I, RUDOLF E. HELLMUND, subject of the Emperor of Germany, and a resident of Swissvale, in the county 5 of Allegheny and State of Pennsylvania, have invented a new and useful Improvement in Systems of Control, of which the following is a specification.

My invention relates to systems of control and especially to direct-current control systems for electric-railway-vehicle motors and the like that are adapted for both accelerating and regenerating operation.

The object of my invention is to provide 15 a system of the above-indicated character which shall be effective and reliable in operation and particularly economical with respect to power requirements, inasmuch as regeneration may be carried to a substantially zero speed of the momentum-driven machines without, however, requiring the use of certain auxiliary machines throughout the entire regenerative period, as has been customary in the prior art.

20 More specifically stated, it is the object of my invention to provide a control system comprising a plurality of main dynamo-electric machines that are governed in accordance with the familiar "series-parallel" control during acceleration and by "parallel-series control" during the regenerative period, dependent upon the machine speed, and, in addition, an auxiliary motor-generator or "booster set" is connected in 25 circuit only under predetermined relatively low-speed conditions, that is, at the beginning of accelerating operation and at the end of the regenerating period only.

My invention may best be understood by 30 reference to the accompanying drawings, wherein Figure 1 is a diagrammatic view of a system of control embodying my invention, the main circuits and the auxiliary-machine circuits being shown; Fig. 2 is a 35 diagrammatic view of one form of auxiliary governing system for controlling the various switching devices shown in Fig. 1, in accordance with the sequence charts, Fig. 3 and Fig. 4, which correspond to acceleration and regeneration, respectively; and Fig. 5 to Fig. 8, inclusive, are simplified diagrams of various sets of connections, as indicated by the accompanying legends.

Referring to Fig. 1, the system shown com-

prises suitable supply-circuit conductors 55 respectively marked "Trolley" and "Ground"; a plurality of main dynamo-electric machines respectively having armatures A1 and A2 and field windings F1 and F2 of the familiar series or heavy- 60 conductor, few-turn type; a reversing switch RS of any familiar type, here shown conventionally for purposes of simplicity and clearness; a plurality of switches for the main and the auxiliary machine circuits LS, JR, J, M, G, and 1 to 5, inclusive; a plurality of main-circuit stabilizing resistors R1 and R2 and auxiliary-circuit resistors 6 to 10, inclusive; a plurality of limit switches L1 and L2 for respectively governing the operation of switches 4 and 5; a voltage relay 19, employed under preliminary regenerative conditions; and a combined motor-generator and exciter set or "booster set" having armatures 20 to 75 23, inclusive, that are preferably mounted upon a common shaft 24 for purposes to be described.

The auxiliary exciting armatures 20 and 21 are respectively adapted to variably 80 energize the main field windings F1 and F2, respectively, throughout the accelerating and the regenerative periods and are provided with shunt field windings 25 and 26, respectively, which may be governed in 85 common by the resistor 10. The auxiliary motor or driving armature 22 is provided with a series-related field winding 27 and with a shunt field winding 28, the energization of which may be varied by suitably 90 manipulating the resistor 8. The auxiliary generator armature 23 is also provided with a series-related field winding 29 and with a shunt field winding 30, the strength of 95 which may be adjusted by the variable resistor 9.

The general operation of the system just described may be stated as follows: initially, the auxiliary-motor armature 22 is connected in series relation with the main 100 series-connected armatures, while the auxiliary-generator armature 23 is connected to the supply circuit to return such energy thereto as is not required for accelerating the main machines and for supplying the 105 small necessary losses, thereby effecting accelerating operation without requiring the use of wasteful resistors. However, as soon

as a predetermined relatively low speed is attained, the "booster set" is excluded from circuit, and, subsequently, "series-parallel control" of a familiar type is employed for governing the main motors.

During regeneration, in general, the opposite sequence of control is utilized, namely, the machines are connected in parallel relation across the supply circuit, under suitable high-speed and voltage conditions, "parallel-series control" is then employed to effect regeneration until a relatively low machine speed is reached, and then the "booster set" is again fully included in circuit to thus effect a continuation of regenerative operation until the main-machine speed is substantially zero. Thus, main-circuit accelerating resistors are eliminated, and a relatively large percentage of the kinetic energy of the momentum-driven machines and vehicle is returned to the supply circuit; but the "booster set" is included in circuit for only a relatively small portion of the operating time and never carries a relatively heavy current, since it is connected in circuit with the main machines only when they are connected in series relation. Consequently, the initial cost and weight and the operating expenses of the "booster set" are correspondingly low.

Reference may now be had to Fig. 2, wherein the auxiliary governing system shown comprises the actuating coils of the various circuit-governing switches shown in Fig. 1; and the variable resistors 8, 9 and 10 which, together with the various actuating coils, are adapted to be suitably governed by a master controller MC that is adapted to occupy a plurality of operative positions *a* to *f*, inclusive, when moved in one direction corresponding to acceleration, and a plurality of operative positions *a'* to *g'* when actuated in the other direction that corresponds to regeneration, a battery B or other suitable source of energy being employed for the purpose of exciting the various actuating coils.

Assuming that it is desired to effect acceleration of the main machines, the master controller MC may be actuated to its initial operative position *a*, whereupon one circuit is established from the positive terminal B+ of the battery B, through conductor 40, control fingers 41 and 42—which are bridged by contact segment 43 of the master controller—the actuating coil of the switch LS and conductor 44 to the negative battery terminal B-.

Another circuit is completed at this time from the contact segment 43, through control finger 45 and the actuating coil of the switch JR, to the negative conductor 44.

Further circuits are simultaneously completed by the engagement of the contact segment 43 with control fingers 46 and 47,

whence circuits are respectively continued through the actuating coils of the switches 2 and 3 to the negative conductor 44.

Referring temporarily to Fig. 1, the circuits established by the closure of the above-mentioned switches may be traced as follows: from the trolley through conductor 50, switch LS, actuating coil 51 of the limit switch or relay L1, main armature A1, stabilizing resistor R1, conductor 52, switch JR, conductor 53, stabilizing resistor R2, conductor 54, main armature A2, conductor 55, actuating coil 56 of the limit switch L2, conductors 57 and 58, switch 2, conductor 59, the auxiliary motor armature 22 and its series-related field winding 27, and conductors 60 and 61 to the negative supply-circuit conductor ground.

An auxiliary-machine circuit is established from the trolley through conductor 62, suitable switch 63, conductors 64, 65 and 66, the shunt field winding 28 for the auxiliary motor armature 22, conductors 67 and 68, switch 3 and conductor 69 to ground.

One terminal of the auxiliary generator armature 23 is connected, through conductor 70, to the positively-energized conductor 65, while the other terminal thereof is connected, through the corresponding series-related field winding 29 and conductor 71, to the negative conductor 61. The shunt field winding 30 for the auxiliary-generator armature 23 has one terminal connected to the positively-energized conductor 70 and its other terminal connected through conductors 72 and 73 to ground.

One brush of the auxiliary exciting armature 20 is connected to conductor 75, whence circuit is completed through the intermittently short-circuited resistor 6, conductor 76, stabilizing resistor R1, conductors 77 and 78, the reversing switch RS and the main field winding F1, in accordance with the usual custom, and conductor 79 to the opposite terminal of the exciting armature 20. One terminal of the other exciting armature 21 is connected, through conductor 80, intermittently short-circuited resistor 7, conductor 81, stabilizing resistor R2, conductor 82, reversing switch RS and main field winding F2, and conductor 83, to the other terminal. The field-winding circuits for the exciting armatures 20 and 21 are established from the positively-energized conductor 64, through conductor 84, to junction-point 85, thence, through the parallel-related field windings 25 and 26 for the respective exciting armatures 20 and 21, to junction-point 86, from which point circuit is completed through conductors 87 and 88 to the negative supply-circuit conductor ground.

Thus, as illustrated in the simplified diagram, Fig. 5, the auxiliary-motor armature 22 is initially connected in series relation with the main machines and is strongly en-

ergized to thereby absorb the greater part of the supply-circuit voltage and effect the impression upon the main machines of a suitably low electromotive force for starting them into operation. The accelerating energy that is not utilized for supplying necessary operating losses is returned to the supply circuit by the auxiliary-generator armature 23. The excitation of the auxiliary 10 exciting armatures 20 and 21 is also relatively great, thereby producing a correspondingly strong field-winding excitation for the main machines, under starting conditions.

15 Upon actuation of the master controller MC (Fig. 2), through the multi-notch position *b*, a series of control fingers 89 that are connected to suitable points of the auxiliary resistor 8 are gradually disengaged 20 from the contact segment 43 to thereby include increasing amounts of the resistor 8 in circuit with the shunt field winding 28 for the auxiliary-motor armature 22. Thus, the auxiliary-motor voltage is gradually reduced to correspondingly increase the voltage applied to the main machines and thus effect an increase of speed thereof.

In position *c* of the master controller, the resistor 10 is gradually inserted in circuit 30 with the field windings 25 and 26 for the exciting armatures 20 and 21, thereby correspondingly weakening the main-field-winding excitation to cause an increase in the speed of the main machines in accordance 35 with familiar principles.

In position *d*, the contact segment 43 first engages control finger 92, whence circuit is completed through the actuating coil of the switch 1 to the negative battery conductor 40 44. Thus, the auxiliary motor armature 22 which, at this time, has impressed upon it a negligible voltage, is short-circuited and entirely excluded from further operation during the accelerating period.

45 A further auxiliary circuit is completed in position *d* of the master controller by the engagement of control finger 93 with the contact segment 43 to effect the excitation of the actuating coil of the switch J. The 50 actuating coil of the switch JR is thereupon deenergized by the disengagement of control finger 45 from the contact segment 43.

In position *e*, contact segment 43 first engages control fingers 94 and 95, whereby the 55 actuating coils of the switches M and G are energized and the actuating coil of the switch J is thereupon deenergized. Furthermore, switches 2 and 3 are opened by reason of the deenergization of their actuating coils in position *e* and thus the auxiliary motor armature 22 and its field winding 28 are entirely disconnected from circuit to thereby reduce the losses in the motor-generator set, which is now driven by the armature 23 acting as a motor.

Without specifically tracing the new main-circuit connections produced by the closure of switches M and G and the concurrent opening of switches JR and J, it is believed that the arrangement of main circuits will be fully understood from Fig. 6, inasmuch as the operation outlined constitutes the familiar "bridging" type of series-parallel transition.

To further effect acceleration of the main 70 machines after their initial connection in parallel relation, the contact segment 43 again successively breaks contact with the control fingers 91 to thus gradually include the auxiliary resistor 10 in circuit with the 80 field windings of the exciting armatures 20 and 21 and thereby reduce the main field-winding excitation, as previously set forth.

Throughout the entire accelerating operation, switches 4 and 5, which normally 85 short-circuit the resistors 6 and 7, respectively, are governed by the limit switches L1 and L2, which are responsive to main-circuit current conditions, thus including the resistors 6 and 7 in circuit with the corresponding auxiliary exciting armatures 90 whenever a relatively high main-armature current obtains to reduce the main field excitation to cause the main-circuit current to subside to a desired normal value. Such 95 control of the switches 4 and 5 is effected by reason of the engagement of contact segment 43 of the master controller with a control finger 96, in all positions of the master controller, whence circuit is completed 100 through conductor 97, coöperating contact members 98 of the limit switch L1, in its upper or high-current position, conductor 99, the actuating coil of the switch 4 and the negative conductor 44. Similarly, a circuit 105 is completed from control finger 100, which corresponds to the control finger 96, through conductor 101, coöperating contact members 102 of the limit switch L2 in its upper position, conductor 103 and the actuating coil 110 of the switch 5 to conductor 44. In this way, relatively great surges or variations of accelerating current are automatically prevented.

Assuming that conditions are suitable for 115 regenerative braking operation, the master controller is first returned to its "off" position, and the main circuit reversing switch RS is then actuated to its reversed position for a familiar purpose. By actuating the 120 master controller to its initial regenerative position *a'*, switches M, G and 1 are first closed by reason of the engagement of a contact segment 109 of the master controller with the corresponding control fingers 94, 125 95 and 92.

The switch LS is not closed to connect the momentum-driven machines to the supply circuit until the voltage of the armatures A1 and A2 has been built up through suitable 130

field excitation from the auxiliary exciting machine 20 to a value preferably slightly above the supply-circuit voltage, whereupon the voltage relay 19 is raised to its upper position to complete the energizing circuit for the actuating coil of the switch LS from the positive terminal of the battery B through conductor 110, coöperating contact members 111 of the voltage relay 19 in its upper or closed position, conductor 112 and the actuating coil of the switch LS to negative conductor 44. As soon as the switch LS has closed, an auxiliary electrical interlock LS—in, which is associated with, and actuated by, the switch LS, in accordance with a familiar practice, bridges the auxiliary contact members 111, thereby rendering the closure of the switch LS subsequently independent of the operation of the voltage relay 19. See simplified diagram Fig. 7.

A brief exposition of the chief function of the stabilizing resistors R1 and R2 will be of value. By reason of the peculiar circuit connections, each resistor carries the corresponding combined main-armature and exciting-armature, or main field-winding, currents. In the case of an incipient increase of main-armature or regenerative current, therefore, the augmented voltage drop across the corresponding stabilizing resistor immediately effects a reduction of the voltage available for delivery to the main field winding from the allied exciting armature, thereby causing a reduction of the regenerative current to a desired normal value. Conversely, an incipient decrease of main-armature current produces an inherent increase of main field-winding current. Thus, the regenerative current is maintained substantially constant, irrespective of supply-circuit-voltage fluctuations and the like. The system just set forth is fully described in my co-pending application, Serial No. 44,443, filed Aug. 9, 1915, patented April 1, 1919, No. 1,298,706.

Upon movement of the master controller through its multi-notch position *b'*, the resistor 10 is gradually short-circuited to thereby increase the excitation of the auxiliary field windings 25 and 26 and correspondingly augment the energization of the main field windings F1 and F2, as the speed of the main machines decreases. Positions *c'* and *d'* are transition notches wherein the main machines are gradually changed over to series relation by the closure of switch J, the opening of switches M and G, the closure of switch JR and the opening of switch J, thus effecting an uninterrupted transition from parallel to series relation without producing any undue current surges.

In position *e'*, the resistor 10 is again gradually short-circuited to correspondingly increase the excitation of the main field windings after the series connection of the

main machines to compensate for the speed decrease thereof. In position *f'*, switch 1 is opened by reason of the disengagement of the contact segment 109 from the control finger 92 just after the engagement of the contact segment with control fingers 46 and 47 to effect the closure of switches 2 and 3. Thus, the "booster set" is again fully included in circuit, the auxiliary armature 22 absorbing the necessary portion of the full voltage in order to maintain regenerative operation of the main machine. See Fig. 8.

To continue regeneration until a substantially zero main-machine speed is attained, the resistor 8 is gradually excluded from circuit in multi-notch position *g'* of the master controller and thus the voltage of the auxiliary armature 22 is gradually increased to compensate for the corresponding decrease of main-machine voltage and speed until a substantially zero speed of the main machines obtains.

Throughout the regenerative period also, the switches 4 and 5 are governed by the limit switches L1 and L2 to prevent surges of regenerative current, in the manner previously described.

I do not wish to be restricted to the specific circuit connections or arrangement of parts herein set forth, as various modifications thereof may be effected without departing from the spirit and scope of my invention. I desire, therefore, that only such limitations shall be imposed as are indicated in the appended claims.

I claim as my invention:

1. In a system of control, the combination with a supply circuit, and a plurality of main dynamo-electric machines adapted for both acceleration and regeneration, of an auxiliary "booster set," means for effecting "series-parallel" control of the main machines, and means for connecting one of the booster-set machines in series-circuit relation with the main machines and another in parallel-circuit relation thereto only under conditions of relatively low accelerating or regenerating main-machine speed.

2. In a system of control, the combination with a supply circuit, and a plurality of main dynamo-electric machines, of an auxiliary "booster set," means for effecting "series-parallel" accelerating control and "parallel-series" regenerative control of the main machines above predetermined machine-speed conditions, and means for connecting one of the booster-set machines in series-circuit relation with the main machines and another in parallel-circuit relation thereto whenever the machines are below predetermined speed conditions.

3. In a system of control, the combination with a supply circuit, and a plurality of main dynamo-electric machines, of auxiliary exciting means for the main-machine field

windings, auxiliary dynamo-electric means for varying the relation of supply-circuit and main-machine voltage, means for employing said dynamo-electric means during 5 only predetermined operating conditions, and means for effecting "series-parallel" control of the main machines under all other conditions.

4. In a system of control, the combination 10 with a supply circuit, and a plurality of main dynamo-electric machines, of auxiliary exciting means for the main-machine-field windings, auxiliary dynamo-electric machines respectively adapted for connection in series relation with and in parallel relation to the main machines, means for employing said auxiliary machines only under predetermined relatively low-speed conditions, and means for effecting "series-parallel" 15 control of the main machines for higher-speed conditions.

5. In a system of control, the combination 20 with a supply circuit, and a plurality of main dynamo-electric machines, of auxiliary machines for variably exciting the main-machine field windings, other auxiliary machines rotatable with the first mentioned auxiliary machines and respectively adapted for connection in series relation with, and 25 in parallel relation to, the main machines, means for employing said other auxiliary machines only under relatively low-speed accelerating and regenerating conditions to 30

vary the relations of supply-circuit and main-machine voltages, and means for effecting "series-parallel" accelerating control and "parallel-series" regenerating control of the main machines for higher-speed conditions. 35

6. In a system of control, the combination 40 with a supply circuit, and a plurality of main dynamo-electric machines, of an auxiliary "booster set," means for connecting one of the booster-set machines in series relation with the main machines and another 45 in parallel relation thereto only under conditions of relatively low-main-machine speed to vary the relations of supply-circuit and main-machine voltages, and means for effecting "series-parallel" control of the 50 main-machines for higher-speed conditions.

7. In a system of control, the combination 55 with a supply circuit, and a plurality of main dynamo-electric machines adapted for both acceleration and regeneration, of an auxiliary motor-generator set, means for effecting "series-parallel" control of the main machines, and means for connecting one of the auxiliary machines in series-circuit relation with the main machines only under 60 conditions of relatively low accelerating and regenerating main-machine speed.

In testimony whereof I have hereunto subscribed my name this 28th day of Feb., 1917.

RUDOLF E. HELLMUND.
